UNITED STATES PATENT OFFICE.

EDWIN L. BUSHNELL, OF POUGHKEEPSIE, NEW YORK.

CAR-SEAT.

SPECIFICATION forming part of Letters Patent No. 461,179, dated October 13, 1891.

Application filed July 9, 1891. Serial No. 398,892. (No model.)

To all whom it may concern:

Be it known that I, EDWIN L. BUSHNELL, a citizen of the United States of America, residing at Poughkeepsie, in the county of 5 Dutchess and State of New York, have invented certain new and useful Improvements in Car-Seats, of which the following is a specification.

My invention relates to that class of car-seats shown in Letters Patent No. 456,015, issued to me July 14, 1891, and particularly to the means for locking the striker-arm to the seat-arm bracket and for protecting the seat-arm from injury in the movement of the 15 striker-arms and back.

In the accompanying drawings, Figure 1 is an end elevation of a car-seat; Fig. 2, a detail view of the lock for securing the striker-arm; and Fig. 3 is a rear view of one end of 20 the seat, a portion only of the seat-back being shown. The back, striker-arms, seat, and general construction and arrangement of the parts are identical with like parts shown in the patent referred to, and need not therefore 25 be particularly described.

The striker-arm on the aisle side is indicated at A, the back at B, the seat at C, and the seat-arm at D. This seat-arm is formed with its under face curved, and this face is 30 lined or shod with a metal strip a, which extends beyond the inner line of the seat-arm toward the striker-arm, and thus forms a bearing or rub-iron for the striker, preventing the abrading of the inner face of the seat-arm. Upon the outer face of the striker-arm and below the under face of the seat-arm is 35 cast or otherwise formed a lug b, which is provided with a recess or cavity c, opening upward and outward, with its longitudinal 40 walls inclined from the front toward the rear, thus making a dovetailed recess, and into this recess the lock, having the bolt d, is inserted from above before the seat-arm is put in place, and as this lug on the striker-arm 45 extends beneath the seat-arm when in place the lock, with its bolt, is prevented from being displaced and requires no further fastening device. The bolt of the lock is operated by means of a key in the ordinary manner. The 50 metal strip a is provided with openings e—

one at each end—with which the bolt is adapted to register and thus lock the back in place. The bolt is the ordinary spring-bolt pressed constantly outward, and after it is retracted to disengage it from the locking-notch the 55 end of the bolt bears against the under face of the strip a, which thus forms a rub-iron for the bolt also until it springs into the notch at the other end of the plate a. As the striker-arms largely aid in supporting the back, and 60 as this strain is too severe for the simple bolt used to lock the parts, I utilize the lug b for this purpose, and to prevent the abrasion of the posts of the seat-arm I continue the ends of the strip a down at each end to protect the 65 wood-work, and against these projecting extensions f the upper edge of the lug bears.

What I claim is—

1. In combination, a car-seat arm, back, and striker-arm, a lug on the striker-arm projecting beneath the seat-arm, a dovetailed recess in said lug opening upward, and a lock in said recess, substantially as described. 70

2. In combination with the seat-arm, back, and striker-arm, the under face of the seat-arm being curved, a lock carried by the striker-arm and projecting beneath the seat-arm, and a strip a of metal secured to the under face of the seat-arm and projecting beyond the inner line of said arm, whereby a 75 rub-iron is provided for the bolt of the lock beneath the seat-arm and for the striker-arm alongside said arm, substantially as described.

3. In combination with the seat-arm, back, and striker-arm, a strip a of metal secured to 80 the under face of the seat-arm and projecting beyond the inner line of said arm to form a rub-iron for the striker-arm, said strip having its ends extending down vertically, and a lug on the striker-arm projecting beneath 85 the seat-arm and adapted to come in contact with the downwardly-extending ends of the strip a, substantially as described. 90

In testimony whereof I affix my signature in presence of two witnesses.

EDWIN L. BUSHNELL.
